UNITED STATES PATENT OFFICE.

ZACHARY T. FRENCH AND WILLIAM C. MEYER, OF BOSTON, MASSACHUSETTS.

SHOE-SEWING MACHINE.

SPECIFICATION forming part of Letters Patent No. 705,063, dated July 22, 1902.

Application filed October 14, 1897. Serial No. 655,165. (No model.)

To all whom it may concern:

Be it known that we, ZACHARY T. FRENCH and WILLIAM C. MEYER, of Boston, county of Suffolk, and State of Massachusetts, have invented an Improvement in Sewing-Machines, of which the following description, in connection with the accompanying drawings, is a specification, like letters and numerals on the drawings representing like parts.

This invention relates to that class of wax-thread sewing-machines especially designed for sewing on the welts of boots and shoes; and it has for its object to improve and simplify the construction of the same, to the end that the stitch-forming devices may work rapidly and the stitches may be uniformly made and firmly set and the locking or crossing point of the two threads may be located midway between the opposite faces of the work or at any other point desired.

In accordance with this invention we provide the machine with devices whereby a measured quantity of needle-thread may be taken from its supply before the commencement of the next stitch to be made and also with means whereby a measured quantity of shuttle-thread may be taken from its supply likewise before the commencement of the next stitch to be made, the measured quantities in each instance being sufficient to form the stitches.

The measured quantities of needle-thread and of shuttle-thread are respectively drawn from their supplies by devices or means independent of the stitch-forming mechanism in the performance of its regular functions, and the stitch-forming mechanism being thus relieved of this work, which heretofore it has had to perform either in whole or in part, is free to operate very rapidly, as neither the take-up nor any other part of the stitch-forming mechanism is overtaxed. Also by thus relieving the stitch-forming mechanism hard tension devices for the threads may be employed, which enables the stitches to be firmly set.

The measured quantity of needle-thread may be drawn off of its supply by the employment of a thread-clamp and pull-off, the former holding the thread while the latter draws a predetermined quantity of it from its supply.

The measured quantity of shuttle-thread may be drawn off of its supply by moving the bobbin rearwardly or away from the work— as, for instance, the shuttle and bobbin may be supported by a suitable shuttle-carrier, and said shuttle-carrier may be moved toward and from the work. When the shuttle-carrier recedes from the work, the shuttle-thread will be drawn off of its supply, and when said shuttle-carrier approaches the work the shuttle-thread thus drawn off will be delivered for the formation of the next stitch.

When the shuttle-carrier recedes from the work and the shuttle-thread is being drawn off, the shuttle is not performing any of its regular or prescribed functions. By employing a shuttle-carrier having a movement from and toward the work we find that as it recedes additional working space is provided for the needle and as it returns the beak of the shuttle may be brought into correct position to enter the loop of needle-thread, and the several parts of the stitch-forming mechanism may be more compactly arranged.

The measured quantity of shuttle-thread is taken from or drawn off of its supply while the needle-thread is held taut—as, for instance, while the needle-thread take-up is in its most elevated position or occupies a position most remote from the work—said take-up at such time holding the needle-thread taut and pulling firmly on the "lock," which is set in the work. By drawing off the shuttle-thread while the needle-thread is so held taut there is no danger of the lock being drawn out of the work; but we do not desire to thus limit our invention, as the needle-thread may be otherwise held taut while the shuttle-thread is being drawn off.

Provision is made whereby the quantity of shuttle-thread drawn off of its supply may be varied in order that the lock may be located at different points between the opposite faces of the work.

The parts are preferably so constructed and arranged that the measured quantity of needle-thread will be drawn off of its supply during the time the take-up rises, which is thereafter given up when the take-up descends, and the measured quantity of shuttle-thread will be drawn off of its supply when the take-up is in its elevated position, holding the nee-

dle-threads taut, and is thereafter given up as the take-up descends; yet the thread-clamp, which holds the needle-thread while a measured quantity is being drawn off, lingers and 5 still holds the needle-thread while the take-up is in its elevated position and while the measured quantity of shuttle-thread is being drawn off. Consequently the measured quantity of shuttle-thread is drawn off while the 10 needle-thread is held positively locked by the thread-clamp.

Also in accordance with this invention the shuttle and needle are adapted to turn on parallel axes, and they are located one in 15 front of the other, and consequently work in parallel vertical planes, and said shuttle and needle are so disposed relative to each other that the vertical planes in which they work are as close together as possible, and when the 20 shuttle is in its extreme forward position its beak will correctly enter the loop of needle-thread and when in its rearward position will provide ample working space for the needle.

Figure 1 shows in front elevation a lock-stitch sewing-machine embodying this invention. Fig. 2 is a left-hand side elevation of 25 the same. Fig. 3 is a right-hand side elevation of the same. Fig. 4 is a side view of the shuttle, shuttle-carrier, and means for operating it; and Fig. 5 is a plan view and partial section of the parts shown in Fig. 4.

The main frame comprises, essentially, the upright standard or column A, surmounted by a table A', having erected thereon several 35 vertical uprights A², which are constructed and arranged to afford bearings for the main shaft B, having secured to it several operating-cams, and said uprights also afford bearings for the rod or bar C and for the other operating parts of the machine.

a represents the wax-pot, which, so far as this invention is concerned, may be of any usual or suitable construction, and it is herein shown as located at the front side of the 45 machine and directly above the tension device b, which latter is or may be of any usual or suitable construction.

c represents a pull-off for the needle-thread which operates in conjunction with other 50 parts to be described to draw off of the thread-supply a measured quantity of thread for the next-stitch, and, as herein shown, (see Fig. 2,) said pull-off consists of a bell-crank lever pivoted at c' to the frame, having a roll c² at the 55 extremity of one of its arms over which the thread 2 passes and having the extremity of its other arm connected by a rod or bar c³ with a slotted arm c⁴, projecting from a hub c⁵, mounted to oscillate on a bar C, supported by 60 the main frame, and to said hub c⁵ a rear-wardly-projecting arm c⁶ is secured, which has at its extremity a stud c⁷, with or without a roll thereon, which enters a cam-groove formed in one side or face of a cam wheel or disk D, which is secured to the main shaft B, said groove being herein shown as formed in the right-hand side or face of said disk.

The rod or bar c³ is adjustably connected with the slotted arm c⁴, so that the pull-off c may be adjusted in such a manner as to operate to pull off more or less needle-thread from the thread-supply, as desired. 70

A thread-clamp is provided next to the pull-off, (see Fig. 2,) by means of which the thread may be held while the pull-off is operated to 75 draw off a measured quantity of thread. The thread-clamp is herein shown as a grooved roll e, over which the thread 2 passes, mounted on a fixed stud e¹, and a thread-engaging finger e², pivoted at e³, having its lower end 80 constructed and arranged to clamp the thread in the groove formed on the periphery of said roll e, and the upper end of said thread-engaging finger is connected by a rod or bar e⁴ with one arm e⁵ of a bell-crank lever pivoted 85 at e⁶, the other arm of said lever projecting rearwardly and having a stud e⁷ at its extremity, with or without a roll thereon, which enters a cam-groove formed in one side or face 90 of the cam wheel or disk D, said groove being herein shown as formed in the right-hand side or face of said disk.

The thread-clamp operates to clamp and hold the needle-thread while the pull-off c draws a measured quantity from the needle-thread supply; but a pull-off and thread-clamp for the needle-thread, whereby a measured quantity is or may be drawn from the thread-supply for the next-stitch to be formed, is shown in our Patent No. 412,703, dated October 3, 1889, so that we do not herein broadly claim such features, except as hereinafter stated. 95

The thread 2 passes from the thread-clamp to an auxiliary take-up, which, as herein 105 shown, consists of a short arm i, pivoted at i' to the main frame and having at its lower extremity a roll over which the thread 2 passes, and having two rearwardly-projecting ears i² i² located a short distance apart, 110 or, in lieu thereof, it may be a slotted arm which receives between them the stud i³, which latter serves as a stop to limit the movement of said arm i in each direction. A spring i⁴ is connected at one end to said 115 arm i and at the other end to the frame, and it operates to draw said arm rearwardly and hold it with one of its projections i² in engagement with the stop i³. As the thread 2 is drawn up by the main take-up, to be described, the auxiliary take-up will yield. The thread 2 passes from the auxiliary take-up to the main take-up, which, as herein 120 shown, consists of an arm m, (see Figs. 2 and 3,) having at its extremity a roll over which 125 the thread 2 passes, said arm being mounted upon the bar C and adapted to vibrate as required, and said arm has at its rear extremity a stud with or without a roll thereon, which enters a cam-groove formed or provided in one side or face of a cam wheel or disk D', which is secured to the main shaft 130 B. The thread 2 passes from the take-up m to the looper n, which is secured to the for-

ward end of a horizontal shaft n' , having its bearings in a part of the framework.

n represents the looper.

- 5 A thread-finger o is provided, which is adapted to carry the needle-thread rearwardly from the looper, and, as herein shown, said thread-finger o is curved and provided with a recessed or grooved end, which receives the thread, and said thread-finger o projects from a hub mounted on a stud o' , and a short arm o^2 projects rearwardly from said hub, the extremity of which is connected by a rod or bar o^3 with the forward end of an oscillating bar o^4 , mounted on the bar C , and the rear 15 end of said bar o^4 has a stud which enters a cam-groove formed or provided in one side or face of the wheel or disk D' , being herein shown as in the right-hand side of said disk.
- p represents the channel-guide, which is secured to an arm pivoted to a projection p' on a transversely-movable feed-slide r , said arm having an upward extension p^2 bearing a roll, which engages a cam wheel or disk D^2 .

20 The feed-slide r is supported in a guide-way r' , formed in the framework, and is adapted to move back and forth in the direction of the feed of the work.

25 The awl s , which in this instance serves only as a feeding-finger, is secured to the end 30 of a gooseneck-arm s' , which is formed or provided with a shank which passes obliquely up through a hole provided for it in the aforesaid projection p' on the transversely-movable feed-slide. The feeding devices, however, are not herein described in detail, as 35 they are included in another application filed by us March 10, 1900, Serial No. 8,196.

40 The welt-guide u , which in this instance also serves as the back gage, is formed with an elongated throat for the passage of the needle t and has also a guideway for the welt, and said guide u is adapted to be moved back and forth or toward and from the work to serve as a rest for the work and also to cooperate with the channel-guide in holding the work stationary while the feeding-awl is brought into engagement with it. The welt-guide u and means for moving it are not herein described in detail, as they form a part 45 of another application filed by us March 10, 1900, Serial No. 8,196.

50 The curved hooked needle t is secured to the needle-segment t' , (see dotted lines, Fig. 3,) which is pivoted to the frame of the machine and which is connected by a short link t^3 , which may be curved more or less, with an arm t^4 , projecting from a hub t^5 , mounted on the bar C , said arm t^4 having a rear extension, which is provided with a stud which enters a 55 cam-groove formed or provided in one side or face of the cam wheel or disk D^2 , said groove being herein shown as formed on the left-hand side of said disk.

55 The shuttle w , which may be of any suitable or usual construction and adapted to contain a bobbin, is set concentrically in a circularly-formed recess in a shuttle-carrier w' ,

having as a part of it a rearwardly-extended bar w^2 , and said shuttle-carrier has suitable bearings in the frame, whereby it is adapted 70 to be moved toward and from the work. The rear end of said bar w^2 is loosely connected to the upper end of an arm w^3 , which is secured to a shaft w^4 , mounted in suitable bearings provided for it at the rear side of the machine, and an arm w^5 is secured to the opposite end of said shaft w^4 , which projects 75 upwardly and has connected to its upper end one end of a connecting-rod w^6 , the opposite end of said rod being connected with a slotted arm w^7 , (see dotted lines, Fig. 2,) projecting 80 downwardly from a hub w^8 , mounted on a stud on the framework, and an arm w^9 projects forwardly from said hub w^8 , which is provided at its extremity with a stud which 85 enters a cam-groove formed or provided in one side or face of the cam-disk D , being in the left-hand side or face of said disk. As said disk D revolves the sliding shuttle-carrier will be moved toward and from the work. 90 As said shuttle-carrier and shuttle move toward and from the work the bobbin contained in said shuttle and disposed concentrically thereto will be correspondingly moved, and it will be seen that as said shuttle-carrier and 95 bobbin are moved rearwardly a predetermined or measured quantity of shuttle-thread sufficient for the next stitch will be drawn from the bobbin, which is thereafter delivered when said shuttle-carrier is moved in a direction toward the work. The movement of the shuttle-carrier will be increased or diminished as required to draw off more or less shuttle-thread by adjusting the end of the connecting-rod w^6 along in the slot in the arm w^7 . 100 As the shuttle-thread is thus drawn from its supply by the receding shuttle-carrier the needle-thread will at such time be held taut by the take-up, which will at such time occupy its most elevated position or will occupy a position most remote from the work, and the lock of the last completed stitch will 105 be set in the work. The needle-thread being thus held taut enables the shuttle-thread to be drawn off without drawing the lock out 110 of the work, which is important, and said taut needle-thread also serves as a point of resistance for the shuttle-thread while it is being drawn off. Also as said shuttle-carrier moves in and out or back and forth it 115 will be seen that when it is in its rearward position ample space is afforded for the descending needle-segment. It will be readily seen that by drawing off the shuttle-thread in this manner in sufficient quantities for the 120 stitches the needle-thread take-up or any other part of the stitch-forming mechanism is not obliged to do this work, as is usual in lock-stitch sewing-machines, which, as heretofore stated, is an important feature in the 125 present machine; but instead of drawing off said shuttle-thread by moving the shuttle-carrier we desire it to be understood that said shuttle-thread may be drawn off of its sup-

ply in many ways and by many different devices independent of the stitch-forming mechanism in the performance of its regular functions, all of which when employed in combination with means also independent of the stitch-forming mechanism in the performance of its regular functions for drawing off measured supplies of needle-thread come within the spirit and scope of this invention.

- 5 10 The shuttle is oscillated by a toothed gear v^{20} , which is engaged by a toothed sector v^{21} , formed at the extremity of an arm v^{22} , projecting downwardly from a hub v^{23} , mounted in the bar C; but herein the movement of the shuttle-carrier toward and from the work is in a line substantially tangential to the arc of the toothed sector v^{21} , so that said shuttle-carrier may be moved toward and from the work regardless of the position of said toothed 15 sector, it being understood that the shuttle-carrier travels but a short distance.

15 The shuttle oscillates on an axis in parallelism with the axis of the needle, and consequently the shuttle-carrier moves toward and from the work in a direction at right angles to the axis of the needle and when in its rearward position provides ample working space for the needle, and when in its forward position its beak will correctly enter the 20 loop of needle-thread.

20 A loop-spreader y is attached to the lower end of an oblique shaft y' , having its bearings in the framework, and the upper end of said shaft has a pinion (see dotted lines, Fig. 25 25) which is engaged by a rack y^2 , formed on or secured to a bar y^4 , which is adapted to slide in a suitable guideway provided for it, and said rack is connected by a link y^5 with the lower end of an arm y^6 , which is pivoted 30 at y^7 to the frame, said arm having an arm y^8 , formed integral with it, which bears a stud which enters a cam-groove formed or provided in one side or face of the cam-disk D.

35 The loop-spreader is located at one side of the needle and is designed to cross in front of the needle and to move in a direction substantially parallel with the axis of the oscillating shuttle, and when so moved it engages the lower thread of the loop on the 40 needle and carries it across in front of the shuttle to thereby form a more or less triangular-shaped loop, which is so held as to receive the beak of the shuttle; but said loop-spreader and means for operating it form the 45 subject-matter of another application filed by us March 9, 1900, Serial No. 7,986.

50 The operation of the machine is as follows: The welt-guide, which is also the back gage, is thrust rearwardly to admit the work. Then 55 said gage comes forward and is locked and the work is held against the channel-guide, which at such time enters the channel in the sole. The needle then comes forward, and at the same time the thread-finger at the opposite side of the work moves rearwardly with the needle-thread, the needle penetrates the work, the take-up gives up its thread, and

the looper carries the thread around the hook of the needle. Then the needle retreats and passes rearwardly with the thread back 70 through the work, and the loop of needle-thread is drawn through. When the needle is thus passed back through the work and is free from the work, the channel-guide moves toward the right into position for the next 75 stitch, and the needle which has thus passed back through the work has the loop of thread thereon, and the loop-spreader is then brought into position to intercept said loop of thread, carrying the lower thread of the 80 loop, which is on the left side of the needle, to one side, spreading the two threads and forming a triangle in front of the shuttle in which the shuttle thereafter enters. The shuttle then oscillates and carries the needle-thread upwardly as a loop, taking said loop away from the needle and disengaging it from the needle and loop-spreader, leaving it free to pass around the shuttle, and at such time the loop thus formed is upon the beak of the 85 shuttle. Meantime while the shuttle is passing through the loop the take-up is descending, the awl-feeding finger comes down upon and engages the work, and the back gage or welt-guide retreats at such time or moves 90 rearwardly to admit of the work being fed along, and the awl-feeding finger is actuated to then feed the work along just previous to the 95 stitch which is thus being formed is set. During the action of the awl-feeding finger in feeding along the work the take-up rises and draws the loop of thread from or off of the 100 shuttle, setting the stitch when or as it arrives at its most extended or remote position from the work. During the time that the 105 take-up rises the thread-clamp operates to clamp the needle-thread, and while the needle-thread is thus clamped the pull-off operates to draw off a supply of needle-thread for the 110 next stitch. The thread-clamp, however, 115 continues to remain in its locking engagement with the needle-thread, while the take-up rises and sets the stitch. When the take-up has arrived at its most extended or remote 120 position from the work, with the needle-thread held taut and the stitch set in the work and the needle-thread still held locked by the 125 thread-clamp, the shuttle is bodily moved rearward in order that a measured quantity of shuttle-thread may be drawn off of the 130 bobbin, which is to be thereafter delivered for the next stitch. The measured quantity of shuttle-thread thus drawn off of its supply is delivered up for the next stitch, while the take-up descends to deliver up its needle-thread.

We have herein referred to the shuttle as having an oscillating movement; yet by such term we intend to include a shuttle having any circular motion about its axis.

We claim—

1. In a lock-stitch sewing-machine, stitch-forming mechanism including a shuttle turning on a horizontal axis and adapted to con-

tain a bobbin, a shuttle-carrier bearing said shuttle, means for moving said shuttle-carrier in a direction at right angles to the axis of said shuttle to bodily move the shuttle and 5 bobbin a predetermined distance away from the work and thereby draw off the bobbin a quantity of shuttle-thread for the next stitch, and to thereafter move said shuttle-carrier in the opposite direction to deliver said shuttle-thread when the next stitch is being formed, 10 and means for holding the needle-thread taut while the shuttle-carrier is moving away from the work, substantially as described.

2. In a lock-stitch sewing-machine, stitch-forming mechanism including shuttle turning on a horizontal axis and adapted to contain a bobbin, a shuttle-carrier bearing said shuttle means for moving said shuttle-carrier in a direction at right angles to the axis of 20 said shuttle to bodily move the shuttle and bobbin a predetermined distance away from the work and thereby draw off the bobbin a quantity of shuttle-thread for the next stitch, and to thereafter move said shuttle-carrier in 25 the opposite direction to deliver said shuttle-thread when the next stitch is being formed, means for varying the extent of movement of said shuttle-carrier, and means for holding the needle-thread taut while the shuttle-carrier is moving away from the work, substantially as described.

3. In a lock-stitch sewing-machine, the combination of stitch-forming mechanism including a needle, a reciprocating shuttle-carrier 35 bearing an oscillating shuttle, means for moving said shuttle-carrier and shuttle away from the work to draw off a supply of shuttle-thread for the next stitch, an adjusting device for varying the extent of movement of 40 said shuttle-carrier, and means for holding the needle-thread taut while the shuttle-carrier is moving away from the work, substantially as described.

4. In a lock-stitch sewing-machine, the combination of stitch-forming mechanism including a needle, a reciprocating shuttle-carrier bearing an oscillating shuttle, means for moving said shuttle-carrier and shuttle away from the work to draw off a supply of shuttle-thread for the next stitch, and means for holding the needle-thread taut while the shuttle-carrier is moved to draw off shuttle-thread, substantially as described.

5. In a lock-stitch sewing-machine, the combination of stitch-forming mechanism including a needle and a shuttle, a thread-clamp for positively clamping and thereby locking the needle-thread at a predetermined time, and means for moving the shuttle-carrier and shuttle away from the work to draw off a supply of shuttle-thread for the next stitch while the needle-thread is locked by said thread-clamp, substantially as described.

6. In a lock-stitch sewing-machine, the combination of stitch-forming mechanism including an oscillating shuttle containing a bobbin, a reciprocating shuttle-carrier bearing

said oscillating shuttle, means including a thread-clamp for holding the needle-thread taut, and means for operating said shuttle-carrier to bodily move the shuttle and bobbin and thereby draw off the bobbin a quantity of shuttle-thread while the needle-thread is held taut, substantially as described.

7. In a lock-stitch sewing-machine, the combination of stitch-forming mechanism including an oscillating shuttle containing a bobbin, a reciprocating shuttle-carrier bearing said oscillating shuttle, means, including a thread-clamp, for holding the needle-thread taut, means for operating said shuttle-carrier to bodily move the shuttle and bobbin and thereby draw off the bobbin a quantity of shuttle-thread for the next stitch while the needle-thread is held taut, and an adjusting device for varying the distance said shuttle-carrier moves, substantially as described.

8. In a lock-stitch sewing-machine, the combination of stitch-forming mechanism including an oscillating shuttle containing a bobbin, a reciprocating shuttle-carrier bearing said oscillating shuttle, means, including a thread-clamp, for holding the needle-thread taut, and means for operating said shuttle-carrier, during the time the shuttle is not performing its regular functions, to bodily move the shuttle and bobbin and thereby draw off the bobbin a quantity of shuttle-thread for the next stitch while the needle-thread is held taut, and thereafter deliver said shuttle-thread when the next stitch is being formed, substantially as described.

9. In a lock-stitch sewing-machine, the combination of stitch-forming mechanism including an oscillating shuttle containing a bobbin, a reciprocating shuttle-carrier bearing said oscillating shuttle, means, including a thread-clamp, for holding the needle-thread taut, and means for moving said shuttle-carrier away from the work to thereby bodily move the shuttle and bobbin and draw off a quantity of shuttle-thread for the next stitch while the needle-thread is held taut by said thread-clamp, and for thereafter moving said shuttle-carrier toward the work to deliver up said shuttle-thread when the next stitch is being formed, substantially as described.

10. In a lock-stitch sewing-machine, stitch-forming mechanism including a needle turning on a horizontal axis, its segment and means for operating it, and shuttle turning on a horizontal axis in parallelism with the axis of said needle, a shuttle-carrier bearing said shuttle, means for moving said shuttle-carrier from and toward the needle, in a direction at right angles to the axis of said needle, to thereby draw off a measured quantity of shuttle-thread and thereafter deliver said shuttle-thread when the next stitch is being formed, and means for holding the needle-thread taut while the shuttle-carrier is moving away from the needle, substantially as described.

11. In a lock-stitch sewing-machine, stitch-

forming mechanism including a needle, its segment and means for operating it and an oscillating shuttle, a shuttle-carrier bearing said oscillating shuttle, means for moving said shuttle-carrier rearward, away from the work, to thereby provide working space for the needle-segment and to draw off a supply of shuttle-thread for the next stitch, and for moving said shuttle-carrier forward, toward the work, to deliver up said shuttle-thread and to bring the beak of the shuttle into correct position to enter the loop of needle-thread, and means for holding the needle-thread taut while the shuttle-carrier is moving away from the work, substantially as described.

12. In a lock-stitch sewing-machine, stitch-forming mechanism including a shuttle oscillating on a horizontal axis, a sliding shuttle-carrier bearing said oscillating shuttle movable in a direction at right angles to the axis of oscillation of the shuttle, means for sliding said shuttle-carrier toward and from the work, and means for oscillating the said shuttle, substantially as described.

13. In a lock-stitch sewing-machine, stitch-forming mechanism including an oscillating shuttle, a sliding shuttle-carrier bearing said oscillating shuttle, means for sliding said shuttle-carrier toward and from the work, and means for oscillating said shuttle comprising a pinion and a vibrating sector, the sliding movement of the shuttle-carrier being substantially tangential to the arc of said sector, substantially as described.

14. In a lock-stitch sewing-machine, the combination of stitch-forming mechanism, means for drawing off a quantity of needle-thread for the next stitch operated independently of the stitch-forming mechanism in the performance of its regular functions and means for drawing off a quantity of shuttle-thread for the next stitch also operated independently of the stitch-forming mechanism in the performance of its regular functions, substantially as described.

15. In a lock-stitch sewing-machine, the combination of stitch-forming mechanism including a needle, an oscillating shuttle and a stitch-setting device, means independent of the stitch-forming mechanism for drawing off a quantity of needle-thread for the next stitch, a shuttle-carrier bearing said oscillating shuttle, and means for moving said shuttle-carrier rearward to draw off a quantity of shuttle-thread for the next stitch while the needle-thread is held taut at the completion of the stitch by the stitch-setting device, substantially as described.

16. In a lock-stitch sewing-machine, the combination of stitch-forming mechanism, a pull-off for drawing off a measured quantity of needle-thread for the next stitch while the take-up rises which is afterward delivered upon the descent of said take-up, and means for drawing off a measured quantity of shuttle-thread for the next stitch while the take-up is holding the needle-thread taut at the com-

pletion of the stitch which is afterward delivered while the take-up descends, substantially as described.

17. In a lock-stitch sewing-machine, the combination of stitch-forming mechanism, a thread-clamp and pull-off for the needle-thread, the latter acting while the thread is clamped to draw a measured quantity of needle-thread off of its supply for the next stitch, 75 a take-up for said needle-thread which operates to set the stitch, and means for drawing a measured quantity of shuttle-thread off of its supply while the needle-thread is held taut by said take-up at the completion of the stitch, and for thereafter delivering up said shuttle-thread for the next stitch, substantially as described.

18. In a lock-stitch sewing-machine, the combination of stitch-forming mechanism, a take-up for the needle-thread, a locking device for said thread, means for drawing off a measured quantity of needle-thread for the next stitch while the needle-thread is locked, 90 and means for drawing off a measured quantity of shuttle-thread for the next stitch also while the needle-thread is locked, substantially as described.

19. In a lock-stitch sewing-machine, the combination of stitch-forming mechanism, a thread-clamp, and pull-off for the needle-thread, the latter acting while the thread is clamped to draw a measured quantity of needle-thread off of its supply for the next stitch, 100 means for taking up the needle-thread and for setting the stitch during which time the needle-thread is drawn taut, and means for drawing a measured quantity of shuttle-thread off of its supply while the needle-thread is thus 105 held taut, substantially as described.

20. In a lock-stitch sewing-machine, the combination of stitch-forming mechanism, means independent of the stitch-forming mechanism for drawing off a supply of needle-thread for the next stitch, and means for drawing off a supply of shuttle-thread for the next stitch while the needle-thread is held taut at the completion of the stitch, substantially as described.

21. In a lock-stitch sewing-machine, the combination of stitch-forming mechanism, means independent of the stitch-forming mechanism for drawing off a supply of needle-thread for the next stitch, and means for drawing off a supply of shuttle-thread for the next stitch during the time the shuttle is not performing its regular functions, substantially as described.

22. In a lock-stitch sewing-machine, the combination of stitch-forming mechanism, a thread-clamp and pull-off for the needle-thread, the latter acting while the thread is clamped to draw a measured quantity of needle-thread off of its supply for the next stitch, 125 a take-up for the needle-thread which operates to set the stitch while the needle-thread is held clamped, and means for drawing a measured quantity of shuttle-thread off of its

supply for the next stitch while the needle-thread is held taut, and during the time the shuttle is not performing its regular functions, substantially as described.

5 23. In a lock-stitch sewing-machine, the combination of stitch-forming mechanism, a thread-clamp, and pull-off for the needle-thread, the latter acting while the thread is clamped to draw a measured quantity of needle-thread off of its supply for the next stitch, a take-up for the needle-thread which operates to set the stitch while the needle-thread is held clamped, and means for drawing off a measured quantity of shuttle-thread while the needle-thread is held clamped and the take-up is holding the needle-thread taut at the completion of the stitch, substantially as described.

24. In a lock-stitch sewing-machine, a needle and a shuttle oscillating on parallel axes, a shuttle-carrier for said shuttle, and means for moving it toward and from the needle in a direction at right angles to the axis of said needle, substantially as described.

25. In a lock-stitch sewing-machine, a needle and a shuttle turning on parallel axes, a shuttle-carrier bearing said shuttle and means for moving it away from the needle in a direction at right angles to the axis of said needle, to provide working space for the needle, and also to draw off a measured supply of shuttle-thread, and for moving it in the opposite direction, toward the needle, to deliver said shuttle-thread and to bring the beak of the shuttle in correct position to enter the loop of needle-thread, and means for holding the needle-thread taut while the shuttle-carrier is moving away from the work, substantially as described.

In testimony whereof we have signed our names to this specification in the presence of two subscribing witnesses.

ZACHARY T. FRENCH.
WILLIAM C. MEYER.
